United States Patent Office

Des. 212,818
Patented Nov. 26, 1968

212,818

DRINKING MUG

Edward P. Flaherty, 2188 N. 31st St.,
Milwaukee, Wis. 53208

Filed Jan. 26, 1968, Ser. No. 10,323

Term of patent 14 years

(Cl. D44—9)

Fig. 1

Fig. 2

FIG. 1 is a side elevational view of a drinking mug showing my new design; and

FIG. 2 is another side elevational view taken from the right of FIG. 1.

I claim:

The ornamental design for a drinking mug, substantially as shown.
